F. KRAEMER.
ELECTRIC SWITCH.
APPLICATION FILED NOV. 27, 1915.

1,208,575.

Patented Dec. 12, 1916

UNITED STATES PATENT OFFICE.

FRANK KRAEMER, OF MILWAUKEE, WISCONSIN, ASSIGNOR, BY DIRECT AND MESNE ASSIGNMENTS, TO PAN-AMERICAN ELECTRIC TOOL COMPANY, OF MILWAUKEE, WISCONSIN, A CORPORATION OF WISCONSIN.

ELECTRIC SWITCH.

1,208,575.

Specification of Letters Patent. Patented Dec. 12, 1916.

Application filed November 27, 1915. Serial No. 63,809.

To all whom it may concern:

Be it known that I, FRANK KRAEMER, a citizen of the United States, residing at Milwaukee, in the county of Milwaukee and 5 State of Wisconsin, have invented certain new and useful Improvements in Electric Switches, of which the following is a specification.

This invention relates to electric switches 10 and has for its object the provision of a switch adapted to make and break a circuit with sufficient rapidity to insure against sparking and consequent burning of the contacts.

15 A further object of my invention is the provision of a device of compact and simple construction whereby the circuit will be closed with sufficient rapidity to prevent sparking when the switch is manually operated and automatically and rapidly broken when the switch is released and which is provided with means for regulating the quantity of current delivered therethrough.

20 Further objects and advantages of my invention will be apparent as it is better understood by reference to the following specification when read in connection with the accompanying drawing disclosing a preferred embodiment thereof in which—

25 Figure 1 is a front elevation of a switch according to my invention; Fig. 2 is a side elevation viewed from the right of Fig. 1; Fig. 3 is a side elevation viewed from the left of Fig. 1 with a portion of the operating handle omitted; Fig. 4 is a horizontal section on the line 4—4 of Fig. 1, and Fig. 5 is a view in perspective of the actuating pawl for the switch.

30 Referring to the drawing, 1 indicates a suitable base of insulating material to which the spindle 2 is secured by means of a suitable bolt 3. Rotatably mounted on the spindle 2 is a member 4 of insulating material, which member is hollowed at 5 to allow a 35 spring 6 to be inserted therein surrounding the bolt 3 and connected to the base 1 at 7 and to the member 4 at 8.

Secured to the upper face of the member 4 is a contact member 9 provided with an 40 arm 10 in which the contact 11 is loosely mounted. The contact 11 is normally held in the position indicated in Fig. 4 by spring

13, to engage the contact points 15 secured to the base 1.

An insulating abutment 16 is mounted on 55 the upper face of the member 4 adjacent the contact 9 and is provided with a sloping shoulder 17. A contact arm 18 is pivotally mounted at 19 on a post 20 secured to the base 1 and is normally held by a spring 21 in 60 position to engage either the abutment 16 or the contact member 9, depending upon the angular position of the member 4.

Slidably mounted in a guide 22 adjacent one end of the base 1 is an operating member 23 having a handle 24, the member 23 being adapted to be reciprocated in a direction longitudinal of the base 1. A spring 25, surrounding the member 23 between the guide 22 and the handle 24, normally forces 70 the member 23 to its outermost position. An arm 26, secured to the inner end of the member 23 connects the latter with a rack bar 27 provided with teeth 28 and slotted at 29, to engage a pin 30 on the base 1 which 75 maintains the rack bar 27 in proper alignment. Pivottally mounted on the pin 30 is a pawl 31 having an abutment 32 thereon adapted to engage a corresponding abutment 33 formed on the member 4, the pawl 80 31 serving as a stop to limit the rotative movement of the member 4 in an anti-clockwise direction under the actuation of the spring 6. Pivottally mounted at 34 on the rack bar 27 is a pawl 35 having a nose 36 85 adapted to coöperate with a tooth 37 on the member 4. A spring 38, secured to the rack bar 27 and to the pawl 35, normally forces the nose 36 thereof into position to engage the tooth 37. A downwardly extending 90 flange 39 on the pawl 35 is adapted to engage and force the pawl 31 into position to allow the shoulder 33 on the member 4 to engage the shoulder 32 on the pawl 31. The member 4 is provided with a mutilated gear 95 comprising the teeth 40 adapted for engagement with the teeth 28 of the rack bar 27.

A resistance element 41 is secured to the underside of the base 1 and the sections 42 thereof are connected by conductors 43 to 100 the contact points 15. The arrangement of the switch in a circuit is illustrated diagrammatically in Fig. 1, in which 44 indicates a source of current and 45 a conductor con-

necting the source of current 44 to the contact arm 18.

46 indicates the electrical apparatus to which the current is supplied, for example a motor, and is connected to the source of current 44 by a conductor 47. A conductor 48 connects the motor 46 to one of the contact points 15, so that the circuit may be completed by operating the switch.

10 The mode of operation of my invention should be apparent from the foregoing without further description of the structure thereof. When it is desirable to close the circuit the operator grasps the handle 24 and 15 moves the member 23 inwardly against the spring 25, thus causing the rack bar 27 and the pawl 35 to move downwardly, viewing Fig. 1. The nose 36 of the pawl 35 being in engagement with the tooth 37 on the member 20 4, the latter will be rotated against the spring 6, thus moving the arm 10, bearing the contact 11, into engagement with the first of the contact points 15. When the member 25 4 has been rotated sufficiently to accomplish this result the contact arm 18 will snap off of the abutment 16 onto the contact member 9, thus rapidly completing the circuit which at 30 this stage includes all of the sections 42 of the resistance element 41. The mechanism is so arranged that the instant the control arm 18 engages the contact member 9 the teeth 28 on the rack bar 27 will engage the teeth 40 on the member 4 and the member 4 may thereby be moved to successively cause the 35 contact 11 to engage the contact points 15 to cut out the sections 42 of the resistance element 41, so that more current is allowed to flow through the switch to the motor 46. As the member 4 rotates under the actuation 40 of the teeth 28 on the rack bar 27 the pawl 31 will be forced outwardly, the member 4 being notched (Fig. 1) adjacent the abutment 33 to receive the abutment 32, and the pawl 31 being therefore forced to ride on the 45 periphery of the member 4 when the member 4 is rotated and will engage the flange 39 to move the nose 36 of the pawl 35 out of engagement with the tooth 37 on the member 4. Should the operator release the handle 50 24 the spring 6 will rotate the member 4 in an anti-clockwise direction and the contact arm 18 will ride onto the abutment 16, thereby by breaking the circuit before the contact 11 leaves the last contact point 15. If the operator releases the handle 24 slowly the member 4 will rotate in an anti-clockwise direction at a corresponding speed until the teeth 40 thereon disengage the teeth 28 on the rack bar 27. Inasmuch as the nose 36 of the pawl 55 35 is held from engagement with the tooth 37, as previously described, the member 4 will rotate rapidly as soon as the teeth 40 disengage the teeth 28 on the rack bar 27 and the breaking of the circuit through en- 60 gagement of the switch arm 18 with the 65

abutment 16 will occur with sufficient rapidity to prevent sparking. In order to again actuate the member 4 to turn in clockwise direction and close the circuit it will be necessary to allow the member 23 to move to 70 its uppermost position whereupon the nose 36 of the pawl 35 will again move into engagement with the tooth 37 under the actuation of the spring 38.

It will be readily understood from the 75 foregoing that I have perfected a switch mechanism whereby the circuit is rapidly made and broken regardless of the speed with which the device is actuated by the operator and of carelessness of the operator 80 in allowing the operating handle to move backward slowly after closing the circuit. The arrangement of the various contacts and the resistance element is such that the circuit when once made is continuous while 85 the flow of current through the switch may be regulated at will without danger of burning the contacts.

I am aware that various changes in the 90 form and proportion of parts and in the details of construction of my invention may be made without departing from the spirit or sacrificing the advantages thereof and I, therefore, reserve the right to make all such 95 changes as fairly fall within the scope of the invention as indicated in the following claims.

I claim:

1. In a device of the character described, the combination of a base, coöperating contact members thereon, one of said members being fixed and the other being arranged to move into engagement therewith, and an auxiliary contact member normally restrained from engagement with one of said 100 contact members and automatically movable to quickly engage said member after said movable member has engaged said fixed member. 105

2. In a device of the character described, the combination of a base, coöperating contact members thereon, one of said members being fixed and the other being arranged to move into engagement therewith, an auxiliary contact arm normally restrained from 110 engagement with said movable contact member and automatically movable to quickly engage said member after said movable member has engaged said fixed member, and means for actuating said movable member. 115

3. In a device of the character described, the combination of a base, coöperating contact members thereon, one of said members being fixed and the other being arranged to move into engagement therewith, an auxiliary contact arm normally restrained from 120 engagement with said movable contact member and automatically movable to quickly engage said member after said movable member has engaged said fixed member, 125

manually controlled means for actuating said movable member in one direction, and means for automatically actuating said movable member to move in the reverse direction.

4. In a device of the character described, the combination of a base, coöperating contact members thereon, one of said members being fixed and the other being arranged to move into and out of engagement therewith, an auxiliary contact arm normally restrained from engagement with said movable contact member and automatically movable to quickly engage said member after said movable contact member has engaged said fixed contact member, manually controllable means for actuating said movable contact member in one direction to close said circuit, and a spring for actuating said movable contact member in the reverse direction to break the circuit.

5. In a device of the character described, the combination of a base, coöperating contact members thereon, one of said members being fixed, a rotatable member supporting the other of said contact members, an auxiliary contact arm normally restrained from engagement with the contact member supported by said rotatable member and automatically movable to engage therewith after said rotatable member has been moved to cause the contact member supported thereby to engage said fixed contact member, and means for actuating said rotatable member comprising a manually reciprocable member, and means providing an intermittent connection between said reciprocating and rotatable members.

6. In a device of the character described, the combination of a base, coöperating contact members thereon, one of said members being fixed, a rotatable member supporting the other of said contact members, an auxiliary contact member normally restrained from engagement with one of said contact members and automatically movable to quickly engage said member after said rotatable member has been moved to cause said coöperating contact members to engage, and means for actuating said rotatable member comprising a reciprocable member, and means carried thereby and adapted for intermittent engagement with said rotatable member.

7. In a device of the character described, the combination of a base, coöperating contact members thereon, one of said members being fixed, a rotatable member supporting the other of said contact members, an auxiliary contact arm normally restrained from contact with the contact member supported by said rotatable member and automatically movable to quickly engage said contact member after said rotatable member has been moved to cause said coöperating contact members to engage.

tact members to engage, and actuating means for said rotatable member including means to insure the quick return of said rotatable member to normal circuit-breaking position when said actuating means is released.

8. In a device of the character described, the combination of a base, coöperating contact members thereon, one of said members comprising a series of fixed elements, a rotatable member to support the other of said contact members, an auxiliary contact arm normally restrained from contact with the contact member supported by said rotatable member and automatically movable to quickly engage said contact member after said rotatable member has been moved to cause said coöperating contact members to engage, and actuating means for said rotatable member including a reciprocable member manually operable in one direction, a pawl carried by said reciprocable member and adapted for intermittent engagement with said rotatable member, and auxiliary interengaging means on said reciprocable and rotatable members.

9. In a device of the character described, the combination of a base, coöperating contact members thereon, one of said members comprising a series of fixed elements, a rotatable member to support the other of said contact members, an auxiliary contact arm normally restrained from contact with the contact member supported by said rotatable member and automatically movable to quickly engage said contact member after said rotatable member has been moved to cause said coöperating contact members to engage, and actuating means for said rotatable member including a reciprocable member manually operable in one direction, a pawl carried by said reciprocable member and adapted for intermittent engagement with said rotatable member, and auxiliary interengaging means on said reciprocable and rotatable members comprising a mutilated gear on said rotatable member and a rack on said reciprocable member.

10. In a device of the character described, the combination of a base, coöperating contact members thereon, one of said members being fixed, a rotatable member supporting the other of said contact members, means for automatically actuating said rotatable member to move in one direction, and means for actuating said rotatable member to move in the opposite direction comprising a reciprocable member, a pawl on said reciprocable member, a tooth on said rotatable member adapted for engagement with said pawl, auxiliary interengaging means on said rotatable and reciprocable members, and means for forcing said pawl from engagement with said tooth after said auxiliary means are engaged and preventing reën-

gagement of said pawl and tooth until said reciprocable member is returned to its initial position.

11. In a device of the character described, the combination of a base, coöperating contact members thereon, one of said members being fixed, a rotatable member supporting the other of said contact members, a spring for automatically actuating said rotatable member to move in one direction, and means for actuating said rotatable member to move in the other direction comprising a reciprocable member manually operable in one direction, a pawl on said reciprocable member, a tooth on said rotatable member adapted for engagement with said pawl, a mutilated gear on said rotatable member, a rack on said reciprocable member for engagement therewith, and means for forcing said pawl from engagement with said tooth after said gear and rack are engaged and preventing reengagement of said pawl and tooth until said reciprocable member is returned to its initial position.
12. In a device of the character described, the combination of a base, coöperating contact members thereon, one of said members being fixed, a rotatable member supporting the other of said contact members, a spring for automatically actuating said rotatable member to move in one direction, and means for actuating said rotatable member to move in the other direction comprising a reciprocable member manually operable in one direction, a spring for returning said reciprocable member to its initial position, a pawl on said reciprocable member, a tooth on said rotatable member adapted for engagement with said pawl, a mutilated gear on said rotatable member, a rack on said reciprocable member for engagement therewith, and means for forcing said pawl from engagement with said tooth after said gear and rack are engaged and preventing reengagement of said pawl and tooth until said reciprocable member is returned to its initial position.

13. In a device of the character described, the combination of a base, coöperating contact members thereon; one of said members comprising a series of fixed elements, a rotatable member supporting the other of said contact members, an auxiliary contact member normally restrained from engagement with one of said coöperating contact members and automatically movable to quickly engage said member after said coöperating contact members are engaged, a spring for actuating said rotatable member to move in one direction, and means for actuating said rotatable member to move in the opposite direction comprising a reciprocable member, a pawl on said reciprocable member, a tooth on said rotatable member adapted for engagement with said pawl, auxiliary interen-

gaging means on said rotatable and reciprocable members, and means for forcing said pawl from engagement with said tooth after said auxiliary means are engaged and preventing reengagement of said pawl and tooth until said reciprocable member is returned to its initial position.

14. In a device of the character described, the combination of a base, coöperating contact members thereon, one of said members comprising a series of fixed elements, a rotatable member supporting the other of said contact members, an auxiliary contact member normally restrained from engagement with one of said coöperating contact members and automatically movable to quickly engage said member after said coöperating contact members are engaged, a spring for actuating said rotatable member to move in one direction, and means for actuating said rotatable member to move in the opposite direction comprising a reciprocable member, manually operable in one direction, a spring to return said reciprocable member to its initial position, a pawl on said reciprocable member, a tooth on said rotatable member adapted for engagement with said pawl, a mutilated gear on said rotatable member, a rack on said reciprocable member, and means for forcing said pawl from engagement with said tooth after said gear and rack are engaged and preventing reengagement of said pawl and tooth until said reciprocable member is returned to its initial position.

15. In a device of the character described, the combination of a base, a movable contact member, contact points in the path of movement of said movable contact member, resistance elements secured to said base and connected to said contact points, whereby the flow of current may be regulated without breaking the circuit, and an auxiliary contact member normally restrained from engagement with said movable contact member and automatically movable to quickly engage said member after said movable contact member has engaged the first of the contact points.

16. In a device of the character described, the combination of a base, a movable contact member, contact points in the path of movement of said movable contact member, resistance elements secured to said base and connected to said contact points, whereby the flow of current may be regulated without breaking the circuit, and an auxiliary contact arm normally restrained from engagement with said movable contact member and automatically movable to quickly engage said member after said movable contact member has engaged the first of the contact points.

17. In a device of the character described, the combination of a base, a contact member, a rotatable member supporting said contact

member, contact points in the path of movement of said contact member, resistance elements secured to said base and connected to said contact points, whereby the flow of current may be regulated without breaking the circuit, an auxiliary contact arm normally restrained from engagement with said contact member and automatically movable to quickly engage said contact member after 10 said rotatable member has been moved to

cause said contact member to engage one of said contact points, and actuating means for said rotatable member, including means to insure the quick return of said rotatable member to normal circuit-breaking position 15 when said actuating means is released.

FRANK KRAEMER.
